UNITED STATES PATENT OFFICE.

CHARLES A. FORD, OF EAST ORANGE, NEW JERSEY.

DESIGN FOR A RING GAUGE.

60,612.

Specification for Design. Patented Mar. 14, 1922.

Application filed April 1, 1921. Serial No. 457,827. Term of patent 3½ years.

To all whom it may concern:

Be it known that I, CHARLES A. FORD, a citizen of the United States, and residing at East Orange, county of Essex and State of New Jersey, have invented a new, original, and ornamental Design for Ring Gauges, of which the following is a specification, reference being had to the accompanying drawing, forming part thereof.

Figure 1 is a front view of the new and ornamental ring gauge, and

Figure 2 is a side view of the ring gauge.

I claim:

The ornamental design for a ring gauge, as shown.

CHARLES A. FORD.
